Inventor:

Joseph Martin

UNITED STATES PATENT OFFICE.

JOSEPH MARTIN, OF MUNICH, GERMANY.

CLAMSHELL.

Application filed August 29, 1921. Serial No. 496,739.

(GRANTED UNDER THE PROVISIONS OF THE ACT OF MARCH 3, 1921, 41 STAT. L., 1313.)

To all whom it may concern:

Be it known that I, JOSEPH MARTIN, a citizen of the German Republic, residing at 40 Bauerstrasse, Munich, Bavaria, Germany, have invented certain new and useful Improvements in Clamshells (for which I have filed applications and obtained patents as follows: Germany, patents filed (a) 26 Feb., 1919, date of grant, 1 Nov., 1921, No. 346,10 966, (b) 6 Feb., 1919, date of grant, 15 July, 1921, No. 341,662; Italy, patent filed 30 June, 1920, application No. 291/268, still pending; Austria, patent filed 1 July, 1920, date of grant, 28 Apr., 1922, No. 89,494; 15 Great Britain, patent filed 2 July, 1920, date of grant, 3 Oct., 1921, No. 169,791; Belgium, patent filed 5 July, 1920, date of grant, 14 Aug., 1920, No. 288,681; France, patent filed, 10 July, 1920, date of grant, 12 Feb., 1921, 20 No. 520,361; Sweden, patent filed 12 July, 1920, application No. 3962/20, still pending; Netherlands, patent filed 11 Aug., 1920, date of grant, 2 June, 1922, No. 7955; Hungary, patents filed (a) 21 Aug., 1920, date of grant, 4 Oct., 1921, No. 80,463, (b) 21 Aug., 25 1920, application No. M6881, still pending; Czechoslovakia, patent filed 27 Nov., 1920, application No. P9103-20, still pending), of which the following is a specification.

30 My invention relates to improvements in clam-shells for handling coal, ore, garbage and the like, and it is one of the essential objects of the invention to provide a clam-shell which is readily movable, and in which means are provided which will cause it (without any additional load) to open reliably in consequence of its own weight and the load of its charge, and in which the proportion of its own weight to the weight 35 of the charge is more favorable than heretofore.

A further object of the invention is to dispose the pulley ropes for closing the clam-shell in such a manner, that they can not be clogged up by dirt and to provide means, preventing undue friction or catching at the ropes and rope pulleys, so that the pulleys will at all times remain readily rotatable and the ropes run properly.

40 These and other objects and advantages of the invention and its design will be fully disclosed in and by the following specification, reference being had to the accompanying drawing, in which

Fig. 1 is a front elevation of the closed 55 clam-shell.

Fig. 2 is a side elevation of the clam-shell.

Fig. 3 shows the clam-shell in open position.

Fig. 4 is the arrangement of the rollers 60 for the pulleys on an enlarged scale, shown partly in section.

In constructing the clam-shell I attach a pair of shells *a* at the ends of long lever-arms *b*, which, at their other ends are pivoted to a common shaft *c*. At both sides of the clam-shell I provide in the lower half of the shells, pulleys *f*, over which ropes *d* are running for closing the clam-shell. At the highest point of the 70 clam-shell, close to the shaft *c* guide pulleys *e* are provided, over which the closing ropes *d* are running in such a manner, that they leave the clam-shell in the plane of its center of gravity. The clam-shell is secured 75 by means of pairs of chains or ropes *i* of constant length to a bridge located above it, this bridge *h* being coupled by a rope *g* to a crane, winch or the like. The said pairs of ropes *i* are attached at the points, where the 80 shells *a* have their maximum width. The width of the bridge *h* is greater than that of both shells together, so that, when the clam-shell is closed (Fig. 1) the pairs of carrier ropes *i* diverge upwardly. Thereby 85 I obtain, that, when the clam-shell begins to open, horizontally extending and outwardly directed opening components will act upon the shell halves. The opening of the clam-shell is effected in the following manner: The bridge *h* is held by its rope *g*, and the closing ropes *d* are slackened. Thereby 90 turning movements are produced, the axes of which lie partly in the ends of the bridge *h*, partly in the points where the ropes *i* act 95 on the shell halves. With the hereinbefore described arrangement the maximum opening moments appear with regard to these points. For the purpose of preventing the pulleys *f* which are fitted to the outside of the shells, to be clogged by dirt, they are covered with hoods *k*. As, nevertheless, the ropes *d* may drag grit or dirt beneath the hoods *k*, which could stick to the grooves of the pulleys and cause the ropes *d* to catch in the hoods *k*, the bottom of the grooves in the pulleys is made, as shown in Fig. 4, flat instead of conical as heretofore, and besides

100 105

much wider than the ropes *d*. I obtain thereby that the ropes can slip on the bottom of the grooves axially to the pulleys, so that they will push aside any particles of dirt dragged into the pulleys, and these will fall off, or, on the other hand, the ropes can be forced aside, to clear the dirt. A further improvement in this direction I obtain by perforating the bottom of the grooves *f* with holes *l*, through which the particles of dirt will be forced so that they can drop down. The edges of these holes will, besides, act as scrapers on the ropes and clean them.

By the hereinbefore described arrangements I obtain a clam-shell, which is—

- 15 1. readily movable,
2. comparatively light with regard to its capacity, and which
3. will close easily, and
- 20 4. will open reliably and quickly at the most favorable utilization of its own weight and the load of the charge.

Having thus described my invention what

I claim as new and desire to secure by Letters Patent is:

25

1. In a clam shell in combination a pair of shells attached to long shell levers pivoted to one another at their extreme ends, a bridge piece above the shells and suspension members of invariable length between the ends of said bridge and the outermost points of the shells, said bridge being of greater length than the distance between the outermost points of the shells in the closed position of the latter.

30

2. In a clam shell in combination a pair of shells rigidly attached to long shell levers pivoted to one another at their extreme ends, a suspension bridge for the shells, and flexible suspension members of invariable length between the ends of said bridge and the outermost points of the shells diverging upwardly in the closed position of the clam shell.

35

In testimony whereof I affix my signature.
JOSEPH MARTIN.
